Application April 27, 1950, Serial No. 158,421
In Czechoslovakia April 29, 1949

9 Claims. (Cl. 42—75)

1

This invention relates to a safety device for a fire arm of the type wherein barrels are frequently changed or removed, and more particularly to an arrangement in which the insertion of the magazine is blocked unless the barrel is properly locked in place. Hitherto, fire arms have had the disadvantage of permitting the insertion of the magazine even though the barrel is not properly locked in place whereby the fire arm may be unintentionally discharged by rotation of the barrel either from firing shocks or from other causes. Such firing may damage or completely ruin the fire arm as well as cause personnel casualty.

This serious disadvantage is overcome according to the instant invention by providing the barrel coupling sleeve and the adjacent part of the breech block casing with cooperating members movable in dependence upon the position of the coupling sleeve in such a way as to permit the magazine of the fire arm to be inserted into the receiver thereof only when the barrel is completely locked in place.

By way of example, an embodiment of the invention is shown in the accompanying drawing wherein like parts are designated by like reference characters and in which:

Fig. 1 is a partial longitudinal section of a fire arm showing the barrel coupling sleeve in locked position;

Fig. 2 is a view similar to Fig. 1 but showing the barrel coupling sleeve unlocked;

Fig. 3 is an end view of the barrel locking sleeve; and

Fig. 4 is a plan view of the barrel locking sleeve. The barrel of the fire arm, which in the case to be described may be considered to be the barrel of a magazine fed machine gun, is removably placed in the casing 2 of the breech block and secured in operative position by a barrel coupling sleeve 3 movably or rotatably mounted on the breech block casing. The coupling sleeve 3 is provided with conventional threads 4 interrupted by longitudinally extending cross cuts 5, the shape and arrangement of which are identical with longitudinal thread segments on the rear end of the barrel 1. To unlock the barrel, the sleeve 3 is rotated by arm 6.

In the upper part of the breech block casing 2 a receiver 7 is formed, the front wall of which is provided with a depression 8 for receiving a cam-like projection 9 on the front wall of the magazine 10. The magazine is further secured in operative position by a spring urged detent member 11 positioned in the rear portion of the

2

receiver 7 for engagement with another projection on the rear wall of the magazine 10. The reference character 12 indicates generally the breech block support governing the function of the fire arm and has no particular function relative to the invention itself.

In order to prevent the loading of the fire arm and/or the insertion of the magazine 10 into the receiver 7, when the barrel 1 is not in place and 10 when the coupling sleeve 3 is loose or unlocked, the construction of parts is arranged so that the barrel coupling sleeve 3 and the adjacent part of the breech block casing are provided with cooperating members movable in dependence upon 15 the position of the coupling sleeve in a manner such as to permit the magazine 10 to be inserted into the fire arm only when the coupling sleeve 3 is in completely locked position. These members comprise a governing member formed in 20 the barrel coupling sleeve 3 and a cooperating member which can be moved into the receiver 7 to block the insertion of a magazine 10 by the rotation of the governing member. In the case considered, the governing member comprises a 25 bent or curved groove 13 in the rear wall of the barrel coupling sleeve 3. Groove 13 is formed with the sleeve preferably in such a manner that the position of its beginning and its end cover the extreme positions of movement, that is the 30 locking and unlocking positions of the coupling sleeve. This means that the groove 13 is of a length equal to the movement of the operating arm 6 of the coupling sleeve from the solidly indicated fully locked position to the dotted unlocked position, both particularly shown in Fig. 3. The groove 13 is not of constant depth throughout its length but is formed so that its depth progresses from the beginning of the groove whereat it is slight gradually toward the 35 end of the groove in a vertical plane through the sleeve 3 whereat it reaches a maximum. The profile of the bottom of the groove can be straight or suitably curved as, for example, a helical or screw shape.

40 Cooperating with the groove 13 is a longitudinally slidable member or pin 15 slidably positioned in a guiding bore in the breech block casing 2 and intermediate the ends of which is an enlarged aperture 16 containing a spring surrounding the pin 15 and positioned between a wall or shoulder of said aperture and a suitable abutment secured to the pin 15. The pin is thereby positioned in the breech block casing 2 opposite the end of the curved groove 13. This 45 slidable member or pin 15 may be formed in vari-

ous manners but in the embodiment shown in the drawing it is shown as a straight pin 15 urged under the pressure of spring 16 in engagement with the bottom of the curved groove 13 of the barrel coupling sleeve 3. The length of the pin 15 is such that the pin in the locked position of coupling sleeve 3 is urged into the deep end of said groove and within its guiding bore so that the opposite end does not project into the receiver 7.

The pin 15 in this normal or locked position does not project into the depression 8 for the cam 9 of the magazine and this permits the magazine and cam to be readily inserted into the receiver 7. If, however, for any reason the barrel coupling sleeve 3 is unlocked or rotated, the sloping bottom of the groove 13 urges the pin 15 rearwardly into the depression 8 and ultimately into the receiver itself, thereby blocking the insertion of a magazine thereinto and warning the operator or gunner to duly lock the barrel coupling sleeve and barrel in place before being able to insert the magazine in preparation for firing.

The safety members, it is to be understood, are not at all limited to the example specified and therefore, can be constructed in other ways without departing from the true spirit and scope of the invention. For example, it is perceived that the groove on the coupling sleeve may be replaced by a profiled projection and the movable safety member arranged as a system of piston rods or levers. The invention also is not limited to fire arms in which the combustion gases are taken off through the barrel but can also be used for fully automatic fire arms. Thus it is intended that the invention can be adapted to use with fire arms fed with ammunition from a cartridge belt, the safety member merely blocking further feed of ammunition thereinto.

Having complied with the statute by particularly describing what is at present believed to be a preferred embodiment of the invention, what is claimed and desired to be protected by the issuance of Letters Patent of the United States is:

1. In a fire arm, a barrel, a breech block casting, a rotatable coupling sleeve adapted to couple and uncouple said barrel to and from said breech block casting, a receiver formed in said breech block casting, a safety member movably mounted in said breech block casting between said receiver and said rotatable coupling sleeve, and means carried by said coupling sleeve for moving said member into said receiver upon rotation of said coupling sleeve.

2. In a fire arm, a barrel, a breech block casting, a rotatable coupling sleeve adapted to couple and uncouple said barrel to and from said breech block casting, a receiver formed in said breech block casting, a pin slidably mounted in said breech block casting between said receiver and said coupling sleeve, and means carried by said coupling sleeve for moving said pin into said receiver upon rotation of said coupling sleeve.

3. In a fire arm, a barrel, a breech block casting, a rotatable coupling sleeve adapted to couple and uncouple said barrel to and from said breech block casting, said coupling sleeve having a locked position determining one limit of its rotation, a receiver formed in said breech block casting, a pin slidably mounted in said breech block casting between said receiver and said rotatable coupling sleeve, resilient means within said breech block casting for urging said pin toward

said coupling sleeve, and means carried by said coupling sleeve for moving said pin against the tension of said resilient means into said receiver upon rotation of said coupling sleeve from its locked position.

4. In a fire arm, a barrel, a breech block casting, a rotatable coupling sleeve adapted to couple and uncouple said barrel to and from said breech block casting, said coupling sleeve having a locked position determining one limit of rotation, a receiver formed in said breech block casting, a pin movably mounted in said breech block casting between said receiver and said rotatable coupling sleeve, said coupling sleeve in the end adjacent said breech block casting having formed therein a groove of gradually increasing depth, spring means carried within said breech block casting urging said pin into the deep end of said groove when said coupling sleeve is in locked position, the pin being of such length that the opposite end of said pin is thereby retracted out of said receiver.

5. In a fire arm, a barrel, a breech block casting, a coupling sleeve rotatable between a locked and unlocked position and adapted to couple and uncouple said barrel to and from said breech block casting, a receiver formed in said breech block casting, said breech block casting having a depression therein adjacent said receiver, a cartridge magazine provided with a front wall and a rear wall, a cam-like projection upon the front wall of said magazine for insertion into said breech block casting depression, a guide bore in said breech block casting extending between said depression and said coupling sleeve, a pin slidably mounted in said guide bore, a groove of increasing depth in said coupling sleeve adjacent said guide bore, a compression spring within said breech block casting normally urging said pin into the deep end of said groove when said coupling sleeve is in locked position, said pin being of a length equal to the length of said guide bore plus the depth at the deep end of said groove, the opposite end of said pin being thereby retracted within said breech block casting and out of said receiver and depression so that said magazine and cam projection thereon may be freely inserted into said receiver and depression respectively, the bottom of said groove sliding said pin against the compression of said compression spring so that said opposite end moves into said depression and receiver as said coupling sleeve is rotated to its unlocked position, said pin thereby blocking the entrance of said magazine and said cam projection thereon into said receiver and depression respectively.

6. In a first arm as set forth in claim 5, in which said groove in said coupling sleeve is curved.

7. In a fire arm as set forth in claim 5, including another projection on the rear wall of said magazine, and spring urged detent means positioned at the rear end of said receiver for co-operation therewith to hold said magazine in place when said pin is retracted from said receiver and depression adjacent thereto.

8. In a fire arm as set forth in claim 6, in which said coupling sleeve and barrel are provided with transverse threads, interrupted by cross cuts on the coupling sleeve and corresponding longitudinal threads on the barrel, whereby the barrel may be slid into place and locked therein by rotation of said coupling sleeve, an operating arm being provided for rotating said coupling sleeve.

9. In a fire arm, as set forth in claim 8, where-
in the length of said curved groove in said cou-
pling sleeve corresponds to the distance between
said cross cuts so that the deep end of said
groove will receive said spring urged pin when
said coupling sleeve is in its locked position,
said pin being against the other end of said
groove when said coupling sleeve is rotated to
its barrel unlocking position.
